UNITED STATES PATENT OFFICE.

RICHARD JOHNSON McCOMB, OF CHICAGO, ILLINOIS.

MANUFACTURE OF SPLICE-BARS FOR COMPROMISE RAIL-JOINTS.

1,333,431.

Specification of Letters Patent.

Patented Mar. 9, 1920.

Application filed January 12, 1920. Serial No. 350,735.

To all whom it may concern:

Be it known that I, RICHARD JOHNSON McCOMB, a citizen of the United States, residing at Chicago, in the county of Cook and State of Illinois, have invented new and useful Improvements in the Manufacture of Splice-Bars for Compromise Rail-Joints, of which the following is a specification.

This invention relates to improvements in the method of manufacturing rail joints or splice bars of the step or offset type and an improved joint bar produced thereby and particularly in the strength thereof at its stepped portion. The improvements of my present invention have in view a more economical production of splice bars of the step joint type and in a manner particularly adapted for producing a more accurately fitting joint possessing improved qualities operative to give adequate support to the rails immediately at the joint or rail ends.

As is well known in railway installations it is oftentimes required that rails of differing section and size shall be joined or connected up in alignment requiring therefor special joint plates which are formed at each end to fit the respective rail sections so as to give proper support thereto. Customarily the "step-joints" so formed are made up of splice bars forged or molded with special dies to mold the bars to conform to and to fit the different rail sections to be connected, which involves objectionable features principally in the course of manufacture incidental to the large number of combinations of rails of different sizes and the corresponding great number of patterns or dies required.

An important feature of my present invention contemplates the manufacture of splice bars from short lengths of standard rolled joint plates for the respective sections or rails to be joined, the short lengths of bar being welded together in an improved manner to give adequate strength at the joint whereby the resulting step joint is peculiarly well adapted to meet the requirements of the conditions to which it is subjected. My improved joint so formed of rolled sections is particularly strong and being formed of sections of joint bars of standard form adapted for the respective rail sections insures accuracy of fit of the splice bars to the "fishing angle" of the respective rail sections whereby they properly engage the rail

head and rail flange in the usual manner. A further and valuable feature of my improved joint resides in the formation of the connecting weld in a manner materially to contribute to the cross sectional area of the joint bars immediately adjacent to the ends of the rails so that additional strength is secured. My improved process of manufacture, as will be readily appreciated permits of conveniently and quickly combining portions of standard rolled joint bars to produce step-joints for the various combinations of rail sections whereby the factor of time in producing a rail joint of a given combination is reduced to a substantial degree.

The aforesaid and other features and advantages of my improved process and step-joint produced thereby will be more fully understood by reference to the following more detailed description and the drawings to be read therewith. In the drawings like reference characters are applied to the corresponding parts in the several views.

Figure 1 is a view in side elevation illustrating a typical compromise or step-joint produced in accordance with my invention.

Fig. 2 is an enlarged and vertical cross sectional view thereof on line 2-2 of Fig. 1.

Fig. 3 is a vertical cross sectional view on line 3-3 of Fig. 1.

Fig. 4 is a similar cross section on line 4-4 of Fig. 1.

Fig. 5 is a plan view of a suitable modification wherein the splice bars are severed angularly.

Referring to the drawings 1 and 2 designate the rail ends which are to be connected, as will be noted the rail 2 being somewhat smaller in cross section than the rail 1 with which it is to be connected. As is obvious in joining rails of different cross section and perimeter specially formed splice bars are required having portions of their length corresponding in size and contour to properly fit the respective rail ends with which they engage. As here shown to rigidly support the rails the usual oppositely disposed splice bars 3, 3 are provided formed for one half part of their length of proper size to fit the rail engaged thereby and at the opposite half of its length similarly formed to fit the other rail of unlike cross section. The splice bars may be of any approved cross sectional contour, for instance of the standard form disclosed having the vertical web portion 4.

2
formed at its upper edge with enlargement 5 provided, with a longitudinally extended bearing surface 6 engaging with the under side of the rail head. The splice bars are 5 also provided at their lower edges with the outwardly extending flanges 7 having their under surfaces 8 fitted to engage with the upper surface of the rail flange 9 longitudinally throughout its length. The splice bars 10 3 are also provided with the usual perforations 10, 10 through their web portions spaced for registration with co-acting bolt receiving apertures 12 in the webs of the respective rails 1 and 2 and adapted to receive 15 the usual clamping bolts not shown.

In accordance with my present invention I form the splice bar of the type described in an improved manner by welding together short lengths of standard rolled splice bars, 20 desirably of the standard angle bar type as illustrated. In the preferred manner of carrying out my invention the standard splice bars are divided centrally of their length by a vertical saw cut and the half length bars so formed are utilized in making up the compromise splice bar by welding together half lengths of the standard bars of appropriate sizes and cross sections properly to engage with the particular and 25 dissimilar rail sections to be joined. In so welding the sections to form the completed splice bar it will be understood that the sections of bar are suitably supported in proper relative position whereby when bolted to the 30 rails to form the rail joint they will properly position and support the rail heads with their inner or tread portions in alignment. The welding together of the sectional lengths of dissimilar splice bars as described may 35 40 be performed by the well known and usual process of electric welding or oxy-acetylene welding as may be desired.

In accordance with further features of my present invention the connecting of the 45 splice bar sections by welding is effected with the addition of metal thereto whereby the resulting connection or joint between the sections will have an enlarged cross sectional area and resulting reinforcement at 50 the point of connection to contribute to and add to the strength thereof. As will be noted the additional strength thus afforded is immediately adjacent to the meeting ends of the connected rails and therefore at the 55 point most desired and important in lending strength to the resulting rail joint. As illustrated, the centrally arranged connecting weld 14 is arranged to extend over a substantial area of each of the connected splice 60 bar sections and is desirably formed with the addition of metal to both the inner and outer sides or surfaces of the standard splice bar sections. The additional welding and reinforcing metal thus provided is welded 65 theron desirably from a bar of steel of simi-

lar composition to that of the standard sections and is melted therewith in the welding operation. The enlargement of the weld longitudinally of the splice bar may also as 70 illustrated be enlarged to the degree permitted and limited by the distance between the inner bolt holes and at its upper edge may be longitudinally flared or enlarged to provide additional area of reinforcement beneath the ends of the rail heads. In the 75 forming of the weld the marginal end surfaces thereof may desirably be tapered off substantially to merge with the surfaces of the connected bars.

I have thus devised an improved method 80 for producing compromise or step joint splice bars which is particularly economical in practice, offers substantial advantages for conveniently and readily producing compromise joints for the various rail combinations and moreover results in the production of a compromise bar having improved properties particularly as to the strength of the joint formed thereby and as to the matter of accuracy in the fit resulting from the use 90 of the standard roll sections. The resulting splice bars are particularly improved in that they are formed without change and distortion of the section or reduction in weight as possessed by compromise joints as 95 heretofore used.

As further contemplated by my invention I desirably heat treat the entire completed splice bar after the weld has been made which treatment may desirably consist of 100 heating to about 1700° F., quenching in oil, reheating from 1200° to 1400° F., quenching in water, again reheating to about 1200° F. and allowing to cool slowly.

While I have described a desirable embodiment of the features of my invention it will be understood that modifications may be made therein without departing from the scope thereof as defined in the appended claims and it is therefore intended that all 110 matter herein shall be interpreted accordingly as illustrative and not in a limiting sense.

As illustrative of a desirable modification I have shown in Fig. 5 a detailed plan view 115 illustrating the forming of the compromise splice bar by severing the respective standard bar sections angularly at approximately a 45° angle instead of at right angles so as to increase the area of the butt weld between 120 the sections at the line of joining. In this view the added metal incorporated in the weld is shown in dotted lines.

Having described my invention, I 125 claim:

1. The herein described method for producing step-joint splice bars which consists in employing sections of standard rolled splice bars of appropriate section to fit the respective rails to be joined and connecting 130

- said splice bar sections by welding, substantially as described.
2. The herein described method of making compromise splice bars for joining rails of dissimilar section which consists in relatively positioning short lengths of standard rolled splice bars of appropriate sizes to fit the respective rails so as to properly engage said rails when in alignment and connecting said short lengths of bars when so positioned by welding, substantially as described.
3. The herein described method of making compromise splice bars for joining rails of dissimilar section which consists in relatively positioning short lengths of standard rolled splice bars of appropriate sizes to fit the respective rails so as to properly engage said rails when in alignment and connecting said short lengths of bars when so positioned by welding with the addition of metal thereto at the joint, substantially as described.
4. The herein described method of manufacturing compromise splice bars adapted for joining rails of dissimilar section which consists in employing therefor short lengths of standard rolled steel splice bars, relatively positioning the short lengths or sections of the splice bars of proper size to fit the respective rails to be joined so as to properly engage the rails when the latter are in alignment and connecting said short lengths of splice bars by welding with the addition of metal thereto in the weld to give greater cross sectional area of the splice bar at the connecting weld and said weld and increased cross section being enlarged longitudinally to comprise a substantial area of the connected bars, substantially as described.
5. The herein described method of manufacturing compromise splice bars adapted for joining rails of dissimilar section which consists in employing therefor short lengths of standard rolled steel splice bars, relatively positioning the short lengths or sections of the splice bars of proper size to fit the respective rails to be joined so as to properly engage the rails when the latter are in alignment and connecting said short lengths of splice bar by welding with the addition of metal thereto in the weld to give greater cross sectional area of the splice bar at the connecting weld, said weld and increased cross section being enlarged longitudinally to comprise a substantial area of the connected bars and said additional metal being added to both the inner and outer sides of the bars in the connecting weld, substantially as described.
6. The herein described method of making compromise splice bars for joining rails of dissimilar section which consists in relatively positioning short lengths of standard rolled splice bars of appropriate sizes to fit the respective rails so as to properly engage said rails when in alignment and connecting said short lengths of bars when so positioned by welding and heat treating the completed splice bar, substantially as described.
7. The herein described method of making compromise splice bars for joining rails of dissimilar section which consists in relatively positioning short lengths of standard rolled splice bars of appropriate sizes to fit the respective rails so as to properly engage said rails when in alignment and connecting said short lengths of bars when so positioned by welding and heat treating the completed splice bar, said heat treatment consisting of heating the bar to about 1700° F. quenching in oil, reheating from 1200° to 1400° F. quenching in water, again reheating to about 1200° F. and allowing to cool slowly, substantially as described.
8. A compromise splice bar adapted for joining rails of dissimilar section consisting of half lengths of standard rolled splice bars of appropriate size to engage the respective rail ends and connected by welding at their abutting ends, substantially as described.
9. A compromise splice bar adapted for joining rails of dissimilar section consisting of half lengths of standard rolled splice bars of appropriate size to engage the respective rail ends and connected by welding at their abutting ends, said connecting weld having an enlarged cross sectional area, substantially as described.
10. A compromise splice bar adapted for joining rails of dissimilar section consisting of half lengths of standard rolled splice bars of appropriate size to engage the respective rail ends and connected by a weld at their abutting ends, said connecting weld being formed with the addition of metal to both the inner and outer surfaces of the respective bars to have an enlarged cross sectional area and said weld being enlarged longitudinally over a substantial area of the connected bar sections.

In testimony whereof I have signed my name to this specification.

RICHARD JOHNSON McCOMB.
